(57) **CLAIM**

The ornamental design for a plasterer's float as shown and described.

DESCRIPTION

1. Plasterer's float

1.1 : Perspective

1.2 : Perspective

1.3 : Right

1.4 : Left

1.5 : Front

1.6 : Back

1.7 : Top

1.8 : Bottom

Plasterer's float which has developed edges which enhance the application of plaster media to substrate.

The claimed design is confined to the "developed" edges of the plasterer's float. The broken lines depict portions of the plasterer's float in which design is embodied that are not considered part of the claimed design.
